DESIGN FOR A CIGARETTE CASE

Gloria Goldman, Los Angeles, Calif.

Application November 27, 1945, Serial No. 124,109

Term of patent 3½ years

(Cl. D85—2)

To all whom it may concern:

Be it known that I, Gloria Goldman, a citizen of the United States of America, residing in Los Angeles, county of Los Angeles, and State of California, have invented a new, original, and ornamental Design for a Cigarette Case, of which the following is a specification, reference being had to the accompanying drawing, forming part thereof, wherein,

Figure 5 is a rear elevational view thereof.

I claim:
The ornamental design for a cigarette case,
substantially as shown.
